DESIGN FOR A SHOWER CURTAIN RING

Herbert D. Schmidt, Little Falls, N. J., assignor to R. D. Werner Co., Inc., New York, N. Y., a corporation of New York

Application January 15, 1946, Serial No. 125,575

Term of patent 3½ years

(Cl. D21—1)

To all whom it may concern:

Be it known that I, Herbert D. Schmidt, a citizen of the United States, residing at Little Falls, in the county of Passaic and State of New Jersey, have invented a new, original, and ornamental Design for a Shower Curtain Ring, of which the following is a specification, reference being had to the accompanying drawing, forming part thereof.

Fig. 1 is a front elevational view of a shower curtain ring, showing my new design.

Fig. 2 is a side view thereof.

I claim:

The ornamental design for a shower curtain ring, substantially as shown.

HERBERT D. SCHMIDT.
